CLAIM

The ornamental design for a finger writing implement, as shown and described.

DESCRIPTION

FIG. 1 is a front perspective view of a finger writing implement showing our new design, the hand depicted by means of broken lines being for illustrative purposes only and forming no part of the claimed design;

FIG. 2 is a front elevational view thereof;

FIG. 3 is a side elevational view with the opposite side being a mirror image thereof;

FIG. 4 is a top plan view thereof;

FIG. 5 is a bottom plan view thereof;

FIG. 6 is a front elevational view of a second embodiment of our new design;

FIG. 7 is a side elevational view with the opposite side being a mirror image thereof;

FIG. 8 is a top plan view thereof;

FIG. 9 is a bottom plan view thereof;

FIG. 10 is a front elevational view of a third embodiment of our new design;

FIG. 11 is a side elevational view with the opposite side being a mirror image thereof;

FIG. 12 is a top plan view thereof; and,

FIG. 13 is a bottom plan view thereof. In FIGS. 2 through 13, the cord has been shown broken away for convenience of illustration.
